AUTOMOBILE RADIATOR ATTACHMENT

Filed Sept. 18, 1920

Patented July 17, 1923.

1,462,403

UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

AUTOMOBILE RADIATOR ATTACHMENT.

Application filed September 18, 1920. Serial No. 411,255.

To all whom it may concern:

Be it known that I, JOHN F. WHITE, a citizen of the United States, residing at Chicago, in the county of Cook and State 5 of Illinois, have invented certain new and useful Improvements in an Automobile Radiator Attachment, of which the following is a specification.

This invention relates to a new attachment 10 for automobile radiators, the same being in the nature of a cap or closure device for the radiator nipple, arranged to carry a temperature indicating instrument or other display device, and constructed in 15 such fashion that it can be secured in place on a radiator nipple of conventional or standard type in a manner to frustrate its unauthorized removal.

The specific mechanism herein disclosed 20 for effecting this object includes in the present instance, a combination lock of any desired or well known construction, the bolt of which, when projected, connects the tube closing cap to a threaded bushing by 25 which the cap is mounted on the automobile radiator nipple. When the bolt is retracted, on the other hand, the device is disconnected from said bushing so that the same cannot be detached from the tube by rotation of the 30 cap. A construction embodying this inventive idea is illustrated in the accompanying drawing, in which—

Fig. 1 is a side elevation and central vertical section of a cap and motor meter mounted on a radiator nipple;

Fig. 2 is a plan view of the same with the motor meter nipple in section on line 2—2 of Fig. 1; and

Fig. 3 is a view from below with the radiator nipple in section.

Fig. 4 is a transverse section of a form of combination lock, same being taken on line 4—4 of Fig. 5.

Fig. 5 is a cross section of the same.

In these views, the numeral 1 designates the nipple of an automobile radiator, 2 the cap and 3 the arms by which the same is rotated. The numeral 4 designates a device sometimes known as a motor meter, the stem 5 of which passes through and is secured by nut 6 to the casing 7 of a combination lock, the internal construction of which may be of a common form and of itself constitutes no part of my invention. One form

of lock which may be utilized is illustrated 55 in Figs. 4 and 5. Such lock includes a substantially cylindrical casing 7 provided with an axial aperture for the passage of the operating member, which in this instance is the stem 5 of the motor meter. Within the 60 casing 7 is slidably mounted the lock bolt 11, adapted to be projected through a side opening in the casing by the spring 20. Means for retaining the bolt retracted within the casing include a freely rotatable ring 21 adapted to engage in a groove 22 in the bolt, and an operating disc 24 having a depending flange 25 adapted to engage an abutment 26 on the bolt. The disc has a central aperture for the passage of the operating member, to which it is operably connected in suitable fashion, as by the lug 27 which fits in a key-way 28 in the stem 5. The ring and disc have engageable members 29, whereby the ring may be rotated in the 75 casing by rotation of the disc. So long as these engaging members are not in engagement, the disc may be rotated independently of the ring. The ring is formed with a clearance recess 30 which, when positioned over the bolt, frees the same from any restraint of the ring, and the flange 25 of the disc also has a clearance recess 31 for the same purpose. Adjacent the recess 31, the flange 25 is deflected inwardly to provide a 85 restoring cam 25^a, which is adapted for co-operation with the abutment 26 on the bolt, whereby the latter may be retracted from extended position upon rotation of the disc. Thus it will be seen that the combination 90 mechanism of the lock is actuated by the stem of the motor meter, the base 8 of which carries the indicating mark 9, which cooperates with the graduations marked 0 to 25 on the top 10 of the cap. By knowledge of 95 the proper combination, the operator may set the clearance recesses 30 and 31 to free the bolt, which then will be free to be projected by its spring 20. The lock casing is fixedly secured to the cap 10 by suitable fastenings 12.

In the present instance the cap does not screw directly upon the radiator nipple, as is customary, but fits rotatably on the outside thereof, as shown in Figs. 1 and 3. An externally threaded bushing 14, which engages threads 15 on the inside of the radiator nipple, is rotatably mounted within the

cap and is held therein by a ring 16, fitted tightly within the cap; it may also be secured therein by screws 17, threaded into the cap adjacent said ring and bearing with their heads against the bottom of the latter. A spring-disk washer 19 is inserted between the cap and the bushing, to detain the cap in desired rotary position when the bolt 11 is retracted. The bushing has an aperture 18 to receive the bolt 11.

The operation is as follows:

When the bolt 11 is freed from the retaining ring 21 and flange 25, it may be projected into the seat, as in Fig. 1, to lock the bushing 14 to the casing 7 and, consequently, to the cap. When, therefore, the cap is rotated to the left, the bushing unscrews from the radiator nipple and the cap and its motor meter can be removed. When the bolt 11 is retracted, the operative connections between the cap and the bushing is removed, so that rotation of the cap has no effect upon the bushing to unscrew it and the cap cannot be removed without again setting the combination. This presents a certain safeguard against theft of the motor meter and obviates the necessity of the car owner or driver carrying a key with him. In the event the relative position of the cap and bushing is not such as to permit the bolt to move directly into the seat 18, the bolt will automatically find such position upon rotation of the cap relative to the bushing, so that further rotation will be effective to unscrew the latter from the nipple.

A feature of the invention is the complete housing of the bushing within the cap as, in this particular embodiment, by the depending circumferential part of the cap, whereby it is rendered impossible for a person not acquainted with the combination to manipulate the bushing or lock mechanism from without.

Various modifications in the details of assemblage of the parts may be made without departure from the spirit of the invention; wherefore the detailed description and the drawing of a particular embodiment are to be taken in an illustrative and not in an unnecessarily limiting sense.

Moreover, while I have illustrated and described the invention as applied to the locking of a radiator cap in position, it will be evident that the same is applicable in many relations to the locking of a cap upon a nipple or stud to prevent unauthorized tampering therewith.

I claim:

1. A theft preventing device comprising, in combination, a rotatable cap, a bushing rotatably connected thereto, a movable locking bolt housed in said cap and arranged to engage the bushing therewith and lock mechanism for securing said bolt in selected po-

sition, said lock mechanism being housed in the cap.

2. An anti-theft device for radiator caps, comprising a threaded bushing mounted to rotate freely within the cap and screw-threaded to engage the radiator nipple, a movable locking bolt housed within said cap and adapted to engage said bushing with said cap when the latter is to be removed, and lock mechanism housed in the cap for securing the bolt.

3. The combination with an automobile radiator cap, of a bushing having rotatable engagement within the cap and threaded to fit the radiator nipple, a combination lock casing secured to the cap, the combination being operable from without, and a locking bolt controlled by said combination to unite the cap and bushing.

4. A lock for automobile radiator caps and the like, comprising a closure cap, a bolt within the same, a lock mechanism housed within the cap and operable from without the same to lock the bolt, and a bushing freely rotatable within the cap and threaded to fit the radiator nipple, said bushing having an aperture to receive said bolt and being secured against axial movement relatively to the cap.

5. An anti-theft device for automobile radiator caps and motor meters, comprising a bushing rotatably held within the cap and threaded to engage the radiator nipple, a combination lock mechanism carried by the cap and operable by the motor meter, the bolt of said lock mechanism engaging said bushing to lock the latter to the cap when it is desired to remove the cap.

6. The combination with an automobile radiator cap, of a combination lock casing protectively housed within the same, a motor meter rotatably mounted on said cap with its stem projecting through said casing and adapted to operate the combination mechanism, a radially movable bolt controlled by said mechanism, and a bushing externally threaded to screw into the radiator nipple rotatably held within the cap, said bushing having an opening to receive said bolt.

7. A protective device for radiator caps and the like, comprising a bushing freely rotatable within the cap and threaded for engagement with the radiator nipple, and lock mechanism also housed within the cap and operable to engage said bushing with the cap when it is desired to remove the latter, said lock mechanism including a concealed portion effective to maintain the cap and bushing disengaged.

8. A closure and the like for automobile radiators including a cap adapted for manual rotation, a bushing rotatably housed therein and adapted to connectively engage the automobile radiator nipple, a bolt

- housed in the cap and operable to connect the bushing and cap to permit rotation of the former by manipulation of the latter, means operable for locking the bolt out of engagement with the bushing and a member operably mounted on the cap and having a manually engageable portion standing above the cap whereby the locking means may be actuated.
9. A closure and the like for automobile radiators comprising a cap adapted for manual rotation, a bushing rotatably housed therein and adapted to connectively engage an automobile radiator nipple, locking mechanism housed within the cap and operable to connect the bushing and cap whereby the former may be rotated by manipulation of the latter, an inspection device having a visible and manually engageable portion extending up from the top of the cap and whereby the locking mechanism may be operated, and means for detaining the cap in selected rotary positions relative to the bushing to maintain a desired position of the indicating device when the locking mechanism is ineffective.
10. An attachment for automobile radiators comprising the combination with a tubular member, of a cap adapted to close the end thereof, a display device mounted thereon, retaining means housed by the cap and tubular member for securing the display device on the cap, and means in the cap and operable by the display device for locking the cap to the tubular member.
11. In a closure attachment for automobile radiators the combination of a collar, a closure cap adapted for rotation on said collar, a bolt housed in the cap for locking engagement with the collar to prevent relative rotation of the cap and collar, and operable lock mechanism housed in the cap for retaining said bolt out of engagement with the collar, said collar being adapted for connection to a radiator nipple to retain the cap in operative position as a closure thereon.
12. An attachment for automobile radiators comprising, in combination, an annular tubular member, a rotatable cap forming a closure for the end thereof, a display device mounted on the cap and having its securing means enclosed by the cap and tubular member, a bolt operably housed in the cap and adapted for locking engagement with the tubular member, and means housed in the cap and operable therein to lock the bolt.
13. An automobile radiator attachment comprising a rotatable cap, a bushing rotatably mounted therein, means frictionally engaging said members to restrain them against relative rotation, said bushing being equipped with means for effecting its attachment to a suitable mounting by rotary movement, and manipulative means housed by the cap for engaging the bushing to permit rotation thereof by the cap.
14. In an automobile radiator attachment, in combination, a bushing arranged for connection to a mounting, a cap covering the bushing to prevent access thereto and having symmetrically arranged handles whereby it may be operated, engaging means carried by the cap for engagement with the bushing to effect adjustment thereof, and means effective upon the cap to restrain it frictionally against rotation relative to the bushing when the engaging means is ineffective.
15. A theft preventing closure for automobile radiators, comprising the combination of a bushing adapted for attachment to the radiator nipple by rotary movement, said bushing having a substantially cylindrical lateral wall portion provided with a laterally opening seat, a closure cap connected to the bushing for co-axial rotation and including a cover portion extending across the top of the bushing and a skirt portion encompassing the lateral wall portion thereof and covering the seat therein, and a movable engaging member housed below the cover portion and operable in said seat to connect the bushing and cap for rotation together.
16. A theft-preventing attachment for automobile radiators, comprising the combination of a bushing adapted for connection to the radiator nipple by rotary movement and having a substantially cylindrical lateral wall portion, a cap connected to the bushing for rotary movement and including a cover portion adapted to close an end of the bushing and support a display device and a depending skirt portion encompassing the lateral wall portion of the bushing, said lateral wall portion being provided with a recess opening laterally adjacent the skirt portion of the cap, and a movable engaging member housed below the cover portion and arranged for engagement in said recess to connect the bushing for rotation with the cap.
17. In a device of the class described, the combination of a bushing adapted for attachment to a suitable mounting by rotary movement said bushing having a top aperture, a cap rotatable relative to the bushing and including a portion encompassing the bushing and a cover portion closing said aperture, and locking means carried by the operating member and movable into engagement with the retaining member to secure the same for rotation with the operating member.
18. An automobile radiator attachment comprising the combination of a bushing adapted for attachment to a radiator nipple, a cap having a skirt portion encompassing

- the bushing and a top portion covering the end thereof, means housed by the cap for connecting it and the bushing for rotation together, laterally extending handles on the cap whereby it may be rotated to connect the bushing to the radiator nipple, and a friction element cooperating with the cap and bushing to restrain them against relative rotation.
- 10 19. An automobile radiator attachment comprising the combination of an annular bushing arranged for connection to a radiator nipple, a cap having an annular portion encompassing the bushing and a top portion covering the end of the same and arranged to accommodate a motor meter, connecting means between said annular portion and the bushing for securing the latter in the cap, and means housed below the top portion of the cap for connecting it and the bushing for rotation together, said means being operable to permit rotation of the cap relative to the bushing.
- 5 20. An attachment for automobile radiators comprising the combination with a tubular member, of a cap adapted to close the end thereof, a motometer mounted thereon with its bulb disposed within the cap and tubular member, and means in the cap and operable by the motometer for locking the cap to the tubular member.
- 15 In testimony whereof I have hereunto signed my name in the presence of two subscribing witnesses.

JOHN F. WHITE.

LEWIS T. GREIST,
FRANCES K. GILLESPIE.

Certificate of Correction.

It is hereby certified that in Letters Patent No. 1,462,403, granted July 17, 1923, upon the application of John F. White, of Chicago, Illinois, for an improvement in "Automobile Radiator Attachments," errors appear in the printed specification requiring correction as follows: Page 1, line 25, for the word "cap" read *device*; page 2, line 14, after the word "seat" insert the numeral *18*; and that the said Letters Patent should be read with these corrections therein that the same may conform to the record of the case in the Patent Office.

Signed and sealed this 9th day of October, A. D., 1923.

[SEAL.]

WM. A. KINNAN,
Acting Commissioner of Patents.
